UNITED STATES PATENT OFFICE.

PHILLIP HIEN, OF CHICAGO, ILLINOIS, ASSIGNOR TO DAVID S. WEGG, OF SAME PLACE.

DESIGN FOR A GRAVITY-ACTING DOG FOR CAR-COUPINGS.

SPECIFICATION forming part of Design No. 33,754, dated December 18, 1900.

Application filed November 24, 1900. Serial No. 37,684. Term of patent 14 years.

To all whom it may concern:

Be it known that I, PHILLIP HIEN, a citizen of the United States, and a resident of Chicago, in the county of Cook and State of Illinois, have invented and produced a new and original Design for a Gravity-Acting Dog for Car-Couplers, of which the following is a specification, reference being had to the accompanying drawings, and to the letters of reference marked thereon, which form a part thereof.

In the drawings, Figure 1 is a front elevation of a device embodying my design. Fig. 2 is a side elevation of the same. Fig. 3 is a rear elevation of the same. Fig. 4 is a top plan view of the same.

As shown in said drawings, the leading or material feature of my design consists of a shank provided with an eye at its upper end adapted to receive a supporting-pivot and having at its lower end a head having a length and thickness greater than the width and thickness of the shank. Said head extends at approximately right angles of said shank and is provided at one end with a contact-surface forming approximately a right angle with

the axis of the head. The other end of said head inclines downwardly and projects below the other parts of the head. The upper surface of said head on one side of said shank ³⁰ inclines downwardly, as indicated in dotted lines on Fig. 1 and as shown in full lines on Fig. 3, and is designed to support a locking-pin having the lower end of the same appropriately formed for engagement thereon. The ³⁵ upper surface of said head on the opposite side of said shank extends at approximately right angles with the axis of the shank.

Having described my invention, what I claim as new, and desire to secure by Letters ⁴⁰ Patent, is—

The design for a gravity-acting dog for car-couplers, substantially as shown and described.

In testimony whereof I have hereunto subscribed my name in the presence of two subscribing witnesses. ⁴⁵

PHILLIP HIEN.
